UNITED STATES PATENT OFFICE.

WILLIAM A. VONCANON, OF MOORESVILLE, INDIANA.

DESIGN FOR A CHAIR.

40,588.

Specification for Design.

Patented Mar. 22, 1910.

Application filed October 3, 1908. Serial No. 456,088. Term of patent 3½ years.

To all whom it may concern:

Be it known that I, WILLIAM A. VONCANON, a citizen of the United States, residing at Mooresville, county of Morgan, State of Indiana, have invented a new, original, and ornamental Design for Chairs, of which the following is a specification, reference being had to the accompanying drawing, forming part hereof.

The figure is a perspective view of a chair showing my new design.

I claim:

The ornamental design for a chair, as shown.

WILLIAM A. VONCANON.
